(57) **CLAIM**

The ornamental design for an X-ray collimator, as shown and described.

DESCRIPTION

FIG. 1 is a front perspective view of an X-ray collimator showing our new design.

FIG. 2 is a rear perspective view thereof.

FIG. 3 is a front side view thereof.

FIG. 4 is a rear side view thereof.

FIG. 5 is a top side view thereof.

FIG. 6 is a bottom side view thereof.

FIG. 7 is a left side view thereof; and,

FIG. 8 is a right side view thereof.

The broken lines depict portions of the X-ray collimator that form no part of the claimed design; the broken lines form no part of the claimed design.
